US00D420134S

United States Patent [19]

Kitayama

[11] Patent Number: Des. 420,134

[45] Date of Patent: ** Feb. 1, 2000

[54] X-RAY COMPUTED TOMOGRAPHY
SCANNER

5,034,970 7/1991 Yahata et al. 378/20

[75] Inventor: **Masahiko Kitayama**, Mitaka, Japan

FOREIGN PATENT DOCUMENTS

[73] Assignee: **Kabushiki Kaisha Toshiba**, Kawasaki,
Japan815713 8/1991 Japan .
846898 9/1992 Japan .
879283 2/1998 Japan .
1004309 3/1998 Japan .[**] Term: **14 Years**

Primary Examiner—Stella Reid

Attorney, Agent, or Firm—Banner & Witcoff, Ltd.

[21] Appl. No.: **29/100,056**

[57] CLAIM

[22] Filed: **Feb. 3, 1999**The ornamental design for x-ray computed tomography
scanner, as shown and described.[51] LOC (7) Cl. **24-01**

DESCRIPTION

[52] U.S. Cl. .... **D24/159**FIG. 1 is a top, front and right side perspective view of x-ray
computer tomography scanner showing my new design,
FIG. 2 is a front elevational view thereof,
FIG. 3 is a top plan view thereof,[58] Field of Search D24/158, 159;
378/4, 19, 20, 21, 113, 137, 146FIG. 4 is a bottom plan view thereof,
FIG. 5 is a right side elevational view thereof, the left side
elevational view being a mirror image,

[56] References Cited

FIG. 6 is a rear elevational view thereof; and,
FIG. 7 is a right side view showing the gantry in tilted
position.
